UNITED STATES PATENT OFFICE.

ROGER F. SCANNELL, OF BOSTON, AND PATRICK J. DUGAN, OF CHESTNUT HILL, MASSACHUSETTS.

CAR-COUPING.

SPECIFICATION forming part of Letters Patent No. 764,308, dated July 5, 1904.

Application filed January 20, 1904. Serial No. 189,821. (No model.)

To all whom it may concern:

Be it known that we, ROGER F. SCANNELL, residing at Boston, Suffolk county, and PATRICK J. DUGAN, residing at Chestnut Hill, Middlesex county, Massachusetts, have invented certain new and useful Improvements in Car-Couplings; and we do hereby declare the following to be a full, clear, and exact description of the invention, such as will enable others skilled in the art to which it appertains to make and use the same.

This invention relates to car-couplings; and it consists in the novel construction and combination of the parts hereinafter fully described and claimed.

In the drawings, Figure 1 is a plan view of the car-coupling. Fig. 2 is an end view of the means for operating the hook.

This invention relates to the class of couplings as shown in the patent to Patrick J. Dugan, No. 748,173, dated December 29, 1903, in which a coupling-hook A is provided which is pivoted to work in a vertical plane.

B is the spring-pressed draw-bar to which the coupling-hook A is pivoted, and C is the guide in which the said draw-bar slides.

D is a portion of the car frame or platform to which the guide C is secured. In order to raise the coupling-hook out of engagement with a similar opposed coupling-hook, the car-frame has a tubular guide E secured to it in a horizontal position at any convenient point adjacent to the coupling.

F is a rod which is journaled in the guide E and provided with a collar e. A spring f is interposed between the collar e and the front end of the tubular guide and when the draw-bar is pushed back in its guide against the pressure of its spring the rod F is pushed back longitudinally in the tubular guide against the pressure of the spring f.

The front end of the rod F has an arm G secured on it, and the free end of this arm is pivoted to a bar g, which is slideable in guides h, secured to the coupling-hook. The bar has stops i, which limit its sliding movement crosswise of the coupling-hook. The sliding movement of the bar permits the hook to be raised when the rod F is partially rotated in its tubular guide.

H is a handle which is connected to the opposite end of the rod F from the arm G and which affords a means for operating it.

What we claim is—

1. The combination, with a car-coupling hook pivoted to work in a vertical plane, of a stationary tubular guide arranged horizontally, a rod journaled in the said tubular guide and provided with an operating-handle, an arm secured to the said rod, and a bar carried by the said coupling-hook and slideable crosswise of it and pivoted to the said arm.

2. The combination, with a stationary guide, a spring-pressed draw-bar slideable therein, and a coupling-hook pivoted to the said draw-bar and working in a vertical plane; of a stationary tubular guide arranged horizontally, a rod journaled in the said tubular guide and provided with a collar, a spring between the said collar and the front end of the said tubular guide, an operating-handle connected to the said rod, an arm secured to the said rod, and a bar carried by the said coupling-hook and slideable crosswise of it and pivoted to the said arm.

In testimony whereof we affix our signatures in presence of two witnesses.

ROGER F. SCANNELL.
PATRICK J. DUGAN.
